US0D1030849S

(12) **United States Design Patent** (10) **Patent No.:** **US D1,030,849 S**
(45) **Date of Patent:** **** Jun. 11, 2024**

(54) **EYE-TRACKING GLASSES**

(71) Applicant: **BELJING 7INVENSUN TECHNOLOGY CO., LTD.**, Beijing (CN)

(72) Inventors: **Yunchao Fan**, Beijing (CN); **Junsheng Li**, Beijing (CN); **Tongbing Huang**, Beijing (CN)

(73) Assignee: **BELJING 7INVENSUN TECHNOLOGY CO., LTD.**, Beijing (CN)

(**) Term: **15 Years**

(21) Appl. No.: **29/713,849**

(22) Filed: **Nov. 19, 2019**

(30) **Foreign Application Priority Data**

Jun. 3, 2019 (CN) 201930283118.3

(51) **LOC (14) Cl.** **16-06**

(52) **U.S. Cl.**

USPC **D16/309**

(58) **Field of Classification Search**

(57) **CLAIM**

The ornamental design for eye-tracking glasses, as shown and described.

DESCRIPTION

FIG. 1 is a front view of eye-tracking glasses, showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a perspective view thereof; and,

FIG. 8 is another perspective view thereof.

(Continued)

The broken lines shown in the figures depict portions of the eye-tracking glasses that form no part of the claimed design.

1 Claim, 4 Drawing Sheets
